Patented Apr. 20, 1920.

FIG. 1

FIG. 2

FIG. 3

Inventor
Jouzus Karasevicz

By his Attorney

Frank Ledermann

UNITED STATES PATENT OFFICE.

JOUZAS KARASEVICZ, OF SOUTH AMBOY, NEW JERSEY.

BABY-COACH AWNING.

1,337,360.

Specification of Letters Patent. Patented Apr. 20, 1920.

Application filed May 29, 1919. Serial No. 300,665.

To all whom it may concern:

Be it known that I, JOUZAS KARASEVICZ, a citizen of Russia, residing at 238 Peltus St., South Amboy, county of Middlesex, and 5 State of New Jersey, have invented certain new and useful Improvements in Baby-Coach Awnings, of which the following is a specification.

This invention has as its object the production of supports, particularly adapted to perambulators or baby carriages, whereby the hood or awning may be adjusted longitudinally of the body of the vehicle, so as to cover any portion thereof at will.

15 A further object is to provide means whereby the awning may be inclined at angle, all of the several adjustments being readily attained by operating single clamp devices on each side of the carriage body.

20 These and other objects are attained by the novel construction and combination of parts hereinafter described and shown in the accompanying drawings, forming a material part of this disclosure and in which—

25 Figure 1 is a perspective view showing a conventional type of baby carriage and indicating the applications of the invention.

Fig. 2 is an enlarged side elevational view showing one of the hood supports, and

30 Fig. 3 is a longitudinal sectional view taken on line 3—3 of Fig. 2.

Referring to the drawings in detail, a conventional type of baby carriage or perambulator is indicated by the numeral 10, 35 the same resting upon pairs of wheels 11 at the front and rear, and provided with a raised handle 12 at the rear.

Attached to the sides of the body 10 along its upper edge and near the ends thereof, 40 are longitudinal brackets having feet 14, containing openings 15 for the reception of securing means, as the screws indicated, the outer ends of the brackets being beveled as shown, while upon the opposite, inner ends 45 are raised transverse elements 16, from which project spaced pairs of lugs 17 receptive of a pair of rails or rods 18, arranged in parallel relation and which are secured by pins or like fastenings 19, the same passing through the extended lugs of the brackets.

Mounted to freely slide on the rails 18

are extensions 20 of rectangular plates 21, having raised circular outer surfaces 22, contactable with sector plates 23, provided 55 with arms 24 extending at right angles therefrom, these arms being connected by arcuate bars 25, and serve to support the angularly disposed frames 26 of the hood or cover 27.

60 Openings are formed in the plate 23 in which are received bushings 28, having reduced portions 29, extending into openings formed in the bracket plate 21. Passing through these bushings are bolts 30 having 65 elongated rectangular heads 31 containing an opening adapted to freely slide upon the rails 18, and extending between the bars 25 and bushings 29, are the coils of compression springs 32, adapted to force the bushings normally outward.

Formed upon the outer sides of the plates 23 are elongated lugs 35, contactable with similar lugs 36 formed upon the inner surfaces of washer plates 33, normally drawn 75 into engagement by the wing nuts 34, suited to receive the screw threads formed upon the outer extending ends of the bolts 30, thus enabling the hood or awning 37 to be secured when extended either horizontally 80 or at an angle to the rails as may be preferred, or adjusted longitudinally thereon.

In operation when it is desired to shift the inclination of the hood, the nuts 34 are loosened from the bolt, the spring retracting 85 the washer 33, and the hood moved into, such position as is desired. The nuts are then set up, compressing the springs 32, forcing the plate 23 tightly against the annular surface 22, and obviously it may be positively 90 held in angular position by means of the engaging lugs 35 and 36.

Having thus described my invention what I claim as new and desire to secure by Letters Patent, is—

95 In a device of the class described, the combination with a hollow body having raised side walls, of foot brackets at the ends of said body near the upper edge thereof, parallel rods extending between said brackets, 100 other brackets slidably engaged with said rods, bolts passing through said brackets, said bolts having elongated heads containing openings engageable with said rods, a hood.

a frame therefor, plates at the converging ends of said frame, bushings passing through openings in said plates, lugs on said plates extending outwardly, washers having corresponding lugs adapted to make contact with the lugs on said plates, and clamp nuts on the threaded ends of said bolts whereby said

washers may be drawn into engagement with said plates holding said hood in an adjusted position angularly and also longitudinally 10 with respect to said rods.

In testimony whereof I have affixed my signature.

JOUZAS KARASEVICZ.
